VENETIAN BLIND CLEANING MACHINE

Earl A. Chamberlin, Cedar Rapids, Iowa

Application March 3, 1941, Serial No. 381,509

11 Claims. (Cl. 15—77)

This invention relates to brushing, scrubbing, and general cleaning devices and has particular relation to a washing, scrubbing, cleaning and drying device particularly suitable for Venetian blinds.

The cleaning of Venetian blinds by the hand method, now commonly used, is a long and arduous task and it is not commercially practicable for this cleaning process to be carried on in quantity production. It is one of the main objects of my invention to provide a machine for cleaning Venetian blinds quickly, thoroughly and economically.

A more specific object of my invention is to provide means for simultaneously and thoroughly cleaning and scrubbing both surfaces of the slats of Venetian blinds and for feeding the slats through the cleaning means automatically and scrubbing, squeegeeing and drying the slats.

Other and further features and objects of the invention will be more apparent to those skilled in the art upon a consideration of the accompanying drawings and following specifications, wherein is disclosed a single exemplary embodiment of the invention, with the understanding, however, that such changes may be made therein as fall within the scope of the appended claims, without departing from the spirit of the invention.

In said drawings:

Figure 1 is a view in side elevation of a Venetian blind cleaning machine constructed according to one embodiment of my invention.

Figure 2 is a view in isometric perspective of the casing of the device shown in Figure 1.

Figure 3 is a view in isometric perspective illustrating diagrammatically the relation of the major parts of the device shown in Figure 1.

Figure 4 is a fragmentary view in top elevation of the device shown in Figures 1, 2 and 3, with the cover removed.

Figure 5 is a fragmentary view in end elevation of one end of the frame of the device shown in Figures 1 and 4 and illustrating in particular the means for discharging and supporting cleaned slats.

Referring now to the drawings:

A cleaning device constructed according to one embodiment of my invention is mounted upon a framework or stand 10 of angle iron or the like including corner uprights 11 and cross bracing members at 12, 13 and 14.

The top of the device includes long rails 16 secured to the uprights 11 and supported by means of legs 17 at the outer ends thereof. The long

rails 16 are provided with cross members (not shown) at one end thereof and this end constitutes a feeding table, indicated generally at 21. The other ends of the rails 16 constitute, along with the members 22, a framework for supporting straps of canvas or the like 23 to act as a table or means for receiving the slats after they have been cleaned.

In general, a device, constructed according to the embodiment of my invention here shown, includes a plurality of longitudinally-extending vertical troughs 24 for supporting Venetian blind slats while they are being fed into the cleaning mechanism. The cleaning mechanism (Figures 3 and 4) includes a plurality of pairs of circular, oppositely-disposed brushes 26, 27 and 28 mounted on a main brush shaft 29. The brush shaft 29 is received in bearings 31 which are mounted in turn on the rails 16.

The means for feeding the Venetian blind slats between the cleaning brushes includes a plurality of vertically disposed pairs of resilient feed rolls 32, 33 and 34. These rolls, which may be of soft rubber or the like, are provided with central shafts 36, the upper end of each of which is journaled in a self-lubricating bearing block constructed of a material such as oil impregnated wood. This bearing block is supported at its ends by brackets 38 extending upwardly from the longitudinal frame rails 16. The feed roll shafts 36 are provided with similar gears 39, each one engaging with the gears of the adjacent feed roll shafts.

The first feed roll or group of rolls is rotated by means of a vertically extending shaft 41 through a gear and belt speed-reduction drive from a motor 42. The speed-reduction drive includes bevel gears 43 and 44, the last of which may be mounted upon a cross shaft 46. This cross shaft is driven by means of a sheave 47, a belt 48, and a small sheave 49 from the brush mounting shaft 29, which shaft is in turn driven by the motor through the large sheave 51, the belt 52, and the small sheave 53 which is mounted upon the motor.

The slats to be cleaned are placed in the troughs 24 and started between the pairs of feed rollers 32, 33 or 34. The rotation of these members then feed the slats between the pairs of opposed rotating brushes 26, 27 or 28 and the brushes, wetted with the cleaning fluid which is held in a semi-circular tank 56 directly below the brushes, will thoroughly clean all grime and dust from the surfaces and edges of the slats.

The troughs 24 are mounted so as to direct the

slats between the brushes and at a spaced distance above the brush mounting shaft 29. In order to prevent the brushes from working the slats down so as to slide against the brush mounting shaft 29, I have provided a transversely extending fold-down roller 57 directly above the troughs 24. This roller is mounted for free rotation between a pair of brackets 58 and 59 which are in turn supported for vertical swinging movement from the bearing mounting brackets 38.

After a slat passes between the scrub brushes, it is fed between a pair of discharge feed rolls, indicated generally at 61. These feed rolls are substantially the same as the ones previously described. The adjacent rollers are driven by the series of meshed gears 62, one gear being mounted on each shaft and one of the rolls being driven by means of the sheaves 63 and 64 and a V belt 66 from the vertical shaft 41.

A third group of similar discharge rolls, indicated generally at 67, are also mounted for rotation in a transversely extending bearing block 68 and inter-connected by means of the spur gears 69, one of the rolls being driven by means of the sheaves 71 and 72 and the V belt 73 along with the feed rolls 61.

This last mentioned group of rolls 67 serves, not only in helping to feed the slats, but also to discharge them from the washing and drying portion of the machine to the slat receiver members 22 and 23, described in greater detail hereinafter.

A hold-down roll 74, somewhat similar to the previously mentioned hold-down roll 57, is supported for free rotative and swinging movement between brackets 76 and 77, these brackets being attached to the bearing block mounting brackets of the second group of feed rolls.

The semi-cylindrical tub 56 for holding the wash water, and the casing for enclosing the scrubbing brushes, are indicated by dotted lines at 81 in Figure 1 and are better shown in Figure 2.

The semi-cylindrical tub 56 is provided at each side with a flanged drain pan 82 and 83 to receive water removed from the slats for conducting it back to the tube. The upper edges of these drain racks, as well as the tub, are bent over as shown at 84, to permit the tub and the racks to hang from the upper edges of the longitudinal frame members 16. The tub is provided with a drain (not shown) to permit it to be readily emptied.

The casing 81 is rectangular in shape and of a size to fit between the frame members 16 to provide a cover for the scrubbing brushes. Flanges 86 are provided at each end of this casing so as to be received over the flanges 84 of the tub to permit the casing to be supported from the same frame members. The cover 87 prevents splashing.

The walls of the casing adjacent the feed rolls 32, 33, 34 and the group of feed rolls 61 opposite thereto are provided with openings indicated generally at 88 and 89. Vertically disposed guide members 91 are positioned on each side of the openings, each guide member being formed to slidably receive the enlarged edge 92a of the squeegee rubbers 92. These squeegee rubbers are mounted so that the adjoining edges of a pair touch each other and thus not only prevent the wash water from splashing out of the casing through the openings but also remove the wash water from the surfaces of the slats after they

have passed between the scrub brushes and as they are leaving the washing compartment.

Although a cleaning solution may be used which will not injure the painted or enameled surface of the slats even if not thoroughly cleaned off, I prefer to provide a series of spray nozzles such as indicated generally at 96. These spray nozzles may be connected to a suitable header or pipe line 97, which header may be supported by straps 98 attached to the gear cover 99 of the last group of feed rolls. Thus the slats may be rinsed with a fine spray of clear water as they pass between the second and third groups of feed rolls and before they are discharged from the machine. I may, however, use a cleaning compound which is non-injurious to paint surfaces and thus entirely eliminate the spray equipment.

If such a sprayer is utilized in rinsing the slats, it is of course preferable that this water be discharged from the machine instead of permitting it to run down into the wash tub 56 where it would dilute the wash water. I have accordingly provided the removable baffle 99 in the drain tray 83 along with a drain 101 which may conduct the rinse water directly to a waste pipe.

The slat receiving structure, indicated at 22 and 23, comprises in general, a number of slat receiving guides 102 positioned so as to receive the slats as they are discharged from each pair of feed rollers 67. Each slat guiding member has a cross sectional shape, as shown in Figure 5, with the top edge flanged as shown at 103 to prevent lateral movement of a slat as long as one end of the slat is held between the feed rolls. The lower edge of each guide member, however, is bent outwardly at an angle of approximately 45 degrees, as indicated at 104 to permit the slat to drop outwardly and downwardly by its own weight as soon as it is discharged from the last feed roll. The slat may then drop down into the canvas receiving straps 23. It is desirable that separate straps be provided for each slat guide member in order that slats of varying lengths may be run through the machine, each size in a separate trough and a separate group of rollers of the machine.

These canvas webs or straps may be attached to the longitudinal frame members 16 by means of metal end plates 106 riveted or otherwise secured to the ends of the straps. The slat guide members 102 are mounted by means of straps 106 above the longitudinally extending angle members 107 which are in turn supported at their ends upon cross frame members 108.

The brushes 28 (Figure 4) are circular in shape and preferably split, as indicated at 111, to provide two semi-circular segments to thus permit the brushes to be removed and replaced or repaired without removing the shaft 29 from the machine. Circular metal mounting plates 112 are preferably fixedly attached, as by welding or the like, upon the mounting shaft 29. The brush segments may be secured to these mounting plates by means of threaded rods or bolts 113 and nuts 114 embedded in the bristles. I may space one pair of brushes, as for instance the brushes 28, further apart than other pairs and the rolls in alignment with this pair of brushes may be of smaller diameter as the rolls at 34 so that thick slats, such as the bottom slat, may be cleaned and dried mechanically in the same manner as the thinner slats.

I have provided a mechanism for quickly and efficiently cleaning Venetian blind slats and one which handles the individual slats without mar-

ring or scratching. Slats of any size, length or shape may be handled.

Although I have described a specific embodiment of my invention, it is apparent that modifications thereof may be made by those skilled in the art. Such modifications may be made without departing from the spirit and scope of my invention as set forth in the appended claims.

I claim as my invention:

1. In a washing machine, at least one pair of substantially vertical feed rolls, means for guiding slats to be washed into the feed rolls, at least one pair of opposed, circular scrubbing brushes disposed for rotation on a horizontal shaft adjacent the discharge side of the feed rolls, a pair of discharge rolls, means for receiving slats discharged from the discharge feed rolls, and means for rotating the feed rolls and rotating the scrubbing brushes.

2. In a washing machine for slats, feed-in rolls, means for guiding slats into the feed-in rolls, circular scrubbing brushes mounted in opposed relation on a substantially horizontal shaft adapted to receive and scrub slats therebetween after discharge from the feed-in roll, and a second set of feed rolls disposed to receive and discharge slats from between the scrubbing brushes, and pliable squeegees disposed adjacent the discharge feed rolls for removing water left on the slats after the washing process.

3. In a washing machine for slats, a pair of scrubbing brushes, means for imparting a scrubbing motion to the brushes, feed rolls for feeding slats between the brushes, substantially U-shaped trough-like means providing horizontal and vertical guides for the slats as they are drawn into the feed rolls, means resisting displacement vertically of the slats from said guide means, other feed rolls for discharging slats from the machine after passing between the scrubbing brushes, and means comprising squeegees for removing water from the slats.

4. In a washing machine for slats, a framework, a plurality of feed-in rolls, substantially U-shaped trough-like guide members for receiving slats and guiding them into the rolls, a plurality of circular scrubbing brushes mounted for rotation upon a transverse shaft and arranged in pairs thereon for receiving slats therebetween after passage through the feed-in rolls, means for discharging the slats from between the brushes and means for removing wash water from the slats.

5. In a washing machine for slats, a plurality of scrubbing brushes, means for feeding slats between the scrubbing brushes, means for discharging slats vertically from the machine after passage between the scrubbing brushes, and means for supporting the forward end of a slat while being discharged by the discharge means until the rear end of the slat has passed completely through the discharge means, said supporting means comprising means for guiding and supporting a slat on one side and at the top thereof, inclined supporting means extending laterally and downwardly below the said guiding means, the said inclined supporting means adapted to slidably support the weight of a slat as long as the slat is held in vertical position by the discharge means and to permit said slat to slide outwardly and downwardly over the face of said inclined supporting means when the slat is released by the discharge means.

6. In a washing machine for slats, a frame, a horizontally disposed shaft mounted thereon, a

plurality of opposed scrubbing members mounted for rotation on said shaft, means for rotating the scrubbing members, a tub disposed generally below the scrubbing members for holding wash water, a casing disposed about and enclosing the upper portion of the scrubbing members, the said casing having openings through the sides thereof for the reception and discharge of slats fed in a vertical plane between the opposed scrubbing members, and means comprising a pair of squeegees for covering each hole in the sides of the casing and for removing wash water from the sides of a slot as it passes through the hole in the side of the casing.

7. In a washing machine for slats, a plurality of scrubbing means, mounted for rotation about a horizontal axis, means for feeding slats into and discharging slats from said scrubbing means, said feeding and discharge means including a plurality of resilient rolls, a shaft extending axially thereof and upwardly from each roll, means for mounting the feeding rolls including means for journaling the upper ends of the said shafts in spaced relation to each other, and gears affixed to the upper ends of said shafts, said gears being meshed with the gears of the next adjacent rolls, and means for driving one roll each of the feed-in rolls and discharge rolls, one of said scrubbing means being disposed in alignment with the median line between every other of the adjacent pairs of resilient rolls whereby a relatively large number of slats may be accommodated in a minimum of space measured transversely of the machine.

8. In a washing machine for slats, a plurality of vertically disposed feed-in rolls, a plurality of pairs of scrubbing brushes, mounted for rotation on a horizontally disposed shaft with the brushes of the pairs mounted in opposed relation, a container for wash water disposed below the brushes so as to immerse the lower portions thereof, discharge rolls for discharging slats from between the scrubbing brushes and for removing the larger part of the wash water from the slats, means for rinsing the slats, and a second set of discharge rolls for discharging the slats from the machine and for removing the rinse water, and means for driving the feed and discharge rolls at substantially the same rate of speed and the scrubbing brushes at a higher rate of speed.

9. In a washing machine for slats, a casing, a drive shaft supported transversely thereof, a pair of circular scrubbing brushes mounted for rotation thereon with the bristles thereof disposed in closely spaced and opposed relation for receiving slats therebetween and above the driving shaft, the said casing adapted to hold washing water to a level lower than the driving shaft, whereby the lower portions of the circular scrubbing brushes are immersed, and means for feeding slats into the casing between the brushes and for discharging slats from the casing.

10. In a washing machine for slats, a casing, a drive shaft supported transversely thereof, a pair of circular scrubbing brushes mounted for rotation thereon with the bristles thereof disposed in closely spaced and opposed relation for receiving slats therebetween and above the driving shaft, the said casing adapted to hold washing water to a level lower than the driving shaft, whereby the lower portions of the circular scrubbing brushes are immersed, the said casing having vertically extending slotted openings in the sides thereof in alignment with the median line of the pair of brushes, flexible means mounted adjacent

said slots for preventing the splashing of wash water outwardly therethrough and for removing excess wash water from a slat after it has passed through the scrubbing brushes, and means for feeding slats into the casing between the brushes 5 and for discharging slats from the casing.

11. In a device of the character described, a supporting frame, a shaft mounted transversely thereof, means for driving the shaft, a plurality of circular scrubbing brushes mounted in pairs 10 thereon with the bristles thereof disposed in closely spaced opposed relation, vertically disposed feeding and discharge rolls mounted on the main frame in spaced relation to the said shaft, a plurality of means for slidably supporting slats in 15

substantially vertical planes and each in alignment with a pair of feeding rolls and a pair of scrubbing brushes, and means for retaining slats in their guiding means comprising a weighted roll disposed transversely above the frame and above the said slats and supported for free vertical movement relative thereto, the said guiding means being disposed vertically relative to the driving shaft so as to direct slats between the brushes above said shaft, the said weighted roll adapted to bias the slats toward their proper positions in the guide means against the tendency of the scrubbing brushes to displace them therefrom.

EARL A. CHAMBERLIN.
